UNITED STATES PATENT OFFICE.

MYER H. LEBOLT, OF CHICAGO, ILLINOIS, ASSIGNOR TO LEBOLT & COMPANY, OF CHICAGO, ILLINOIS, A CORPORATION OF ILLINOIS.

DESIGN FOR A WEDDING-RING.

51,209.

Specification for Design.

Patented Aug. 28, 1917.

Application filed July 11, 1917. Serial No. 180,000. Term of patent 3½ years.

To all whom it may concern:

Be it known that I, MYER H. LEBOLT, a citizen of the United States, residing at Chicago, in the county of Cook and State of Illinois, have invented a new, original, and ornamental Design for Wedding-Rings, of which the following is a specification, reference being had to the accompanying drawings, forming part thereof.

In the drawing,

The figure is a perspective view of a wedding ring embodying my design.

I claim:

The ornamental design for a wedding ring, as shown.

MYER H. LEBOLT.
